UNITED STATES PATENT OFFICE.

NICHOLAS SCHROEDER, OF MONOHAN, AND JOHN SUTTER, OF ISSAQAH, WASHINGTON.

AUTOMATIC DRAFT-CONTROLLER.

1,179,763.

Specification of Letters Patent. Patented Apr. 18, 1916.

Application filed April 28, 1915. Serial No. 24,414.

To all whom it may concern:

Be it known that we, NICHOLAS SCHROEDER and JOHN SUTTER, citizens of the United States, residing at Monohan and Issaquah, respectively, in the county of King and State of Washington, have invented certain new and useful Improvements in Automatic Draft-Controllers, of which the following is a specification.

10 This invention relates to improvements in dampers for stoves, furnaces and the like, and the object of our improvements is to provide a damper of cheap, and simple construction that is automatic in its operation 15 and may easily be applied to a stove or furnace of the usual form of construction.

The invention consists in the novel construction, adaptation and combination of parts, as will be hereinafter described and 20 claimed.

25 In the accompanying drawings, Figure 1 is a view in longitudinal vertical section of devices embodying this invention; Fig. 2 is a view in front elevation of the same to a reduced scale; and Fig. 3 is a view in vertical section on broken line 3—3 of Fig. 1.

Referring to the drawings, the reference numeral 5 designates the cylindrical wall of a shell or casing having at one end a peripheral flange 6 and is desirably constructed of sheet metal. The flange 6 is apertured to receive bolts which serve to secure the casing in front of an opening 8 provided in a wall 8 of a stove and below 35 the grate thereof if the latter is used.

9 represents an annular washer of asbestos or an equivalent material interposed between the casing flange and said stove wall; said washer having an internal diameter less than that of the casing to extend within the latter and serve as a seat for the hereinafter described damper plate. Provided for the outer end of said casing wall is a removable end comprising a plate 10 and a 40 collar 11 adapted to fit snugly into such wall and constitutes a part of the casing. The plate 10 is provided with a plurality of symmetrically disposed sector-shaped openings 12, indicated by broken lines in 45 Fig. 2, which are adapted to register with the similar shaped openings 13 in a damper or regulating plate 14 when the same is suitably rotated about a pivotal pin 15 by which the regulating plate is secured to the casing 50 plate 10.

55 The regulating plate 14 is advantageously

provided with a protuberance 16 whereby it may be turned to open or close the openings 12, such turning movements being limited by the length of a slot 17 on the regulating plate and a pin 18 protruding therethrough from the casing end 10.

The casing wall 5 is provided in proximity to the flange 6 with a plurality of circumferentially disposed air inlet openings 19.

Within the shell 5 is provided a disk 20 of preferably a concavo-convex form and of somewhat less diameter than the inner diameter of the casing. Said disk is rigidly secured to a horizontal channel bar 21 which is suspended by vibratory parallel links 22 and 23 from a channel bar 24 fixedly secured to the top of the casing wall 5. Said links are pivotally connected with the respective channel bars by pins 21¹ and 24¹ whereby the disk 20 is movable lengthwise of the casing and maintained rectangular to the axis thereof.

The position of the disk 20 is governed by a weight 25 adjustably disposed on the horizontal limb 26 of a weight arm 27 that is connected with one of the links, as 22, and extends upwardly through a slot 28 in the top of the casing wall 5.

To prevent fuel, ashes and the like, from entering the casing through the opening 8¹, we have provided an ash shield 30 to be secured to the inside of the furnace wall 8, as by brackets 31, to cover the opening 8¹. The inner end of this ash shield 30 is provided with perforations 32 of sizes to prevent coarse material from entering and at the bottom the shield is provided with a cut-away portion or opening 33 whereby ashes or other material may escape without entering the casing.

The operation of the invention is as follows: The device is applied as shown in Fig. 1 and the weight 25 is adjusted so as to normally hold the disk 20 from the seat provided by washer 9 and into substantially the position in which it is shown by full lines in Fig. 1. The regulator plate 14 is then turned to close the openings 12 in the front wall of the casing until the fire is lighted and is burning briskly. With the opening 12 closed, air for combustion purposes will be drawn in through the openings 19, as indicated by arrows A. When the fire is burning briskly under a strong draft through the openings 19 and regulator plate

14 is turned to open more or less the holes 12 and permit air to be drawn in through such holes to flow around the periphery of the disk 20, as indicated by arrows B, a current 5 is created longitudinally through the casing that tends to move the disk 20 forwardly into the position shown by broken lines in Fig. 1 to thereby temporarily shut off the draft and accordingly check the fire. As 10 the fire is thus affected, the current of air through the casing is interrupted and the disk 20 is moved from its seat on washer 9, thus permitting a new current of air to be established which, upon becoming unduly 15 strong, will influence the disk 20 to arrest the same, and so on. The damper thus operates automatically and may be controlled to regulate the current for the maintenance of either a hot or a moderate fire by moving 20 the weight 25 on the arm 26 to increase or diminish the suction necessary to move the disk 20, but subject to the effective sizes of opening 12, as determined by the adjustment of the regulator plate.

25 What we claim, is—

1. A device of the class described, comprising a cylindrical casing having an inner open end, and air inlet perforations adjacent the inner end thereof, an apertured plate 30 for the outer end of said casing, a damper plate having its periphery spaced from the peripheral wall of said casing, yieldable means supporting said damper plate for movement longitudinally of said casing whereby said damper plate may be moved 35 to close the open end of the casing when subjected to a relatively strong current of

air admitted into the casing through the apertures of said plate, and means for closing such apertures whereby said yielding 40 means is capable of retaining the damper plate in open position with respect to the open end of the casing and thereupon air for combustion purposes is supplied through the medium of said perforations irrespective of the demand.

2. A device of the class described, comprising a casing having an air-intake opening at its outer end, an air-outlet opening at its inner end and an intake opening in its 50 periphery in proximity to its inner end, a damper-plate of less diameter than the inner diameter of said casing, means for supporting said damper-plate for movements longitudinally within the casing, a weight 55 operatively connected to said damper-plate for yieldingly retaining the latter in position intermediate the outer intake opening and the intake opening in the periphery of the casing, and adjustable means for 60 regulating the effective size of said outer opening or for entirely closing the same, said last-named means serving to render the weight inoperable to influence the damper-plate to close the outlet opening with respect to the intake opening in the periphery 65 of the casing.

Signed at Issaquah, Wash., this 19th day of April, 1915.

NICHOLAS SCHROEDER.
JOHN SUTTER.
